UNITED STATES PATENT OFFICE.

WALTER MUNCH, OF SUPERIOR, WISCONSIN, ASSIGNOR TO SYPHONIX REFRIGERATOR COMPANY, A CORPORATION OF DELAWARE.

SHOW CASE.

Application filed April 5, 1927. Serial No. 181,061.

This invention relates to refrigerated show cases and has special reference to a division wall for such show cases.

The principal object is to provide a novel form of division wall for show cases to facilitate assembly.

Other objects and advantages of the invention will appear in the further description thereof.

10 Referring now to the accompanying drawing, forming part of this application, and wherein like reference characters indicate like parts:

Figure 1 is a transverse vertical section 15 through a superimposed show case, showing the novel form of division wall in elevation;

Figure 2 is a horizontal section on the line 2—2 of Figure 1; and

Figure 3 is an enlarged horizontal sectional 20 view of the resilient cooperative connection of the free end of the division wall with the front glass of the show case.

1 represents the top member of the show case, while 2 is the bottom member thereof, the show case being illustrated as superimposed upon any form of upright structure as indicated at 3. 4 represents one of the rear hinged doors for access to the interior of the refrigerator, said doors in this instance being provided with inner and outer spaced glass panels 5 and 6, and 7 and 8 represent similar spaced glasses in the front wall of the show case, the latter glasses being somewhat inclined. The show case here illustrated is one 35 particularly designed for use with an electrically operated refrigerant, or the like, preferably installed in a compartment adjacent one end of the show case, and this compartment is formed by the installation of a

40 partition or division wall indicated at 12—13 spaced from the end 10 of the show case. Now the principal novel feature of this division wall is that it is supported entirely from the innermost edge thereof, as by being nailed or otherwise rigidly fastened as at 11, or in any other suitable manner to the back wall 11' of the show case, and is substantially equally spaced from both the top and bottom of the show case so as to per-

mit of free circulation of air to and from the display portion of the show case and in and about the refrigerant.

The preferred construction of the division wall comprises a comparatively thin board-like section of suitable insulating material as indicated at 12, having upon either side thereof a porcelain facing indicated at 13, and at the front edge of the division wall or partition the porcelain facing projects beyond the edge of the insulating board and securely impinges therebetween the edges of a strip of flexible packing or the like, shown at 14, and so held between the porcelain facings as to normally form a bead-like projection therefrom, so that when the glass 8 is placed in position in the front of the show case it will bear more or less forcibly against this yieldable bulb or bead of packing and insure a tight joint between it and the glass. The bead being of a resilient material will insure against breakage during assembly or rough handling of the show case.

15 and 16 represent longitudinally disposed shelves within the display portion of the show case.

From the foregoing it is evident that I have devised a very simple and practical assemblage of division wall within a show case, and one that may be readily positioned therewith prior to the placing of the front panels 80 or glass within the show case, and when the latter is accomplished a perfectly tight joint is assured between the innermost glass and the division wall.

Having thus described my invention, what I claim and desire to secure by Letters Patent, is:

A division wall for a refrigerated show case comprising two upright spaced members attached at one side thereof to a vertical wall of the show case, insulating material intermediate of said members, the free ends of the spaced members overlapping the free end of the insulating material, and a resilient member held intermediate of the overlapped edges of the spaced members.

In testimony whereof I affix my signature.
WALTER MUNCH.
